ATTORNEY

UNITED STATES PATENT OFFICE.

SAMUEL C. HOEY, OF WILKINSBURG, PENNSYLVANIA, ASSIGNOR TO WESTINGHOUSE ELECTRIC & MANUFACTURING COMPANY, A CORPORATION OF PENNSYLVANIA.

PROCESS OF AND APPARATUS FOR PRESSURE CASTING.

Application filed July 14, 1923. Serial No. 651,558.

To all whom it may concern:

Be it known that I, SAMUEL C. HOEY, a citizen of the United States, and a resident of Wilkinsburg, in the county of Allegheny and State of Pennsylvania, have invented a new and useful Improvement in Processes of and Apparatus for Pressure Casting, of which the following is a specification.

My invention relates to a process of and 10 an apparatus for casting metal bodies and more especially to the casting under pressure of the conductor members in the rotors of dynamo electric machines.

It is among the objects of my invention 15 to provide an apparatus for casting metal bodies under pressure which shall be of simple, compact, mechanical construction, which shall be simple to operate and adapted to the production of metal bodies in an expedient and inexpensive manner.

It is a further object of this invention to provide a device which shall be capable of preventing the flaws in castings incident to the usual processes of casting molten metal 20 under pressure.

It is well known that the pressure casting of molten metal as ordinarily practiced produces a body having blow-holes and fallen surfaces caused by cooling, especially at the 30 portion of the casting farthest away from the charging port of the mold.

To overcome this difficulty, I propose to counteract the tendency of the material to shrink by mechanical forces exerted in such 35 manner and at such time as will compact the metal at the portion where shrinkage takes place, at the instant that the mold is filled. By means of this process, the body produced is of uniform strength and the 40 blow-holes are substantially eliminated so that the casting has a homogeneous structure throughout.

In the accompanying drawing constituting a part hereof and in which like reference 45 characters designate like parts,

The single figure is a view, partially in vertical section and partially in elevation, of a casting device embodying the principles of my invention.

50 The device comprises a base 1, constituting a reservoir for molten metal, having operatively mounted therein a piston 2 which is adapted to traverse in a vertical direction to raise the metal through a plurality

of port holes 3 into the matrix 4 of a mold 5 which is secured to the top of the base 1. The mold 5 includes a base plate 6 and a clamping plate 7, the latter having an annular opening 8 adapted to receive a flanged ring 9 which is vertically movable therein. 60 A piston 10 is connected to suitable actuating means in co-operative alignment with the pressure ring 9 to effect a downward movement thereof when the piston is actuated. 65

A rotor 11 comprising a plurality of superposed sheet iron laminations is secured between the base plate 6 and clamping plate 7 of the mold by means of a bolt 12 which has a screw thread engagement with 70 the base plate 6. The mold is formed to provide a plurality of annular spaces 13 and 14 at the respective ends of the rotor 11, which is provided with slots or openings 15 communicating with the spaces 13 and 14. 75 The metal occupying the slots 15 and the end spaces 13 and 14 constitutes the conductor bars and end rings, respectively, of the rotor when cast.

The operation of the device is briefly as 80 follows: The lower piston member 2 is actuated to exert a pressure on the molten metal in the reservoir causing it to rise and forcing it through the vertical ports 3 into the spaces 13, 14 and 15 in the rotor and 85 the mold against the top clamping plate 7. When the mold is filled, the upper piston 10 is actuated downwardly after a predetermined period which is just previous to the complete setting or hardening of the 90 metal while it is still somewhat plastic so that the pressure has the desired effect in compressing the metal. This operation produces a casting that has a homogeneous grain structure and further produces a well 95 formed and completely filled body that may be cast to the desired dimensions, thereby obviating the need of machining.

It will be obvious to those skilled in the art that the various mechanical features of 100 my device may be altered to adapt it for any specific form of casting and that any suitable apparatus may be utilized for carrying out my invention without departing from the spirit thereof. 105

I claim as my invention:

1. A method of casting bodies which comprises filling a mold with molten metal

- under pressure and exerting additional pressure on the casting so formed before the metal is set.
2. A method of casting bodies which comprises filling a mold with molten metal under pressure and exerting an additional pressure on the casting so formed at a predetermined time after the body is cast.
3. A method of casting bodies which comprises filling a mold with molten metal under pressure and exerting a counteracting pressure on the casting so formed before the metal is set.
4. A method of casting bodies which comprises filling a mold with molten metal under pressure and then compressing the casting so formed before the metal is set.
5. A method of casting bodies which comprises filling a mold with molten metal under pressure and exerting pressure on the body so formed at the end opposite the charging end.
6. A device for casting bodies under pressure comprising a mold, a reservoir there-
for, a plurality of communicating ports 25
between said mold and reservoir, a pressure
actuated piston in said reservoir, and
another piston for the other end of said
mold.
7. A device for casting bodies under pres- 30
sure comprising a reservoir constituting a
base for a mold mounted thereon, a plurality
of pistons associated with said reservoir
and mold and means for securing a rotor
to be cast in the latter.
8. A device for casting bodies under pres- 35
sure comprising a base, a mold mounted
thereon, a reservoir comprising the inner
chamber of said base, a plurality of com-
municating ports for said mold and reser- 40
voir means for mounting a member to be
cast in said mold, a piston for discharging
said reservoir and a piston for compacting
the discharge in the said mold.
- In testimony whereof, I have hereunto 45
subscribed my name this 2nd day of July
1923.

SAMUEL C. HOEY.
